UNITED STATES PATENT OFFICE.

JOSEPH C. CROPPER, OF CEDAR FALLS, IOWA.

ROLLER-SKATE.

SPECIFICATION forming part of Letters Patent No. 314,916, dated March 31, 1885.

Application filed April 19, 1884. (No model.)

To all whom it may concern:

Be it known that I, JOSEPH C. CROPPER, a citizen of the United States, residing at Cedar Falls, in the county of Black Hawk 5 and State of Iowa, have invented certain new and useful Improvements in Roller-Skates; and I do hereby declare that the same are fully described in the following specification and illustrated in the accompanying drawings.

10 This invention relates to improvements in roller-skates, and it is carried out as follows, reference being had to the accompanying drawings, where—

Figure 1 represents a side elevation of the 15 improved skate. Fig. 2 represents an end view thereof, as seen from X in Fig. 1. Fig. 3 represents a cross-section on the line A B, as seen from Y in Fig. 1. Fig. 4 represents a bottom view of one of the bearings with its 20 rollers. Fig. 5 represents a longitudinal section on the line C D shown in Fig. 4, and Fig. 6 represents a cross-section on the line E F shown in Fig. 1.

Similar letters refer to similar parts wherever they occur on the different parts of the 25 drawings.

a represents the wooden or metal sole-plate, as usual, having heel-strap b in its rear end, or any other well-known or equivalent device 30 vice for securing the rear end of the roller-skate to the foot.

To two opposite sides of the forward part of the sole-plate a is secured the arched toe-strap c, of a size and shape proportionate to that of 35 the size of the skate, by which means the forward end of the skate can be most easily secured to the toe portion or instep of the skater's boot or shoe simply by inserting and pushing the forward end of the foot into such 40 arched strap, after which the rear end of the skate may be secured in any desirable manner.

To the under side of the sole-plate a is secured the metal bearing-block d (one in each end of the said sole-plate) by means of suitable fastening-screws or in other well-known 45 manner. The bearing-block d has side webs, d' d'', cast in one piece with its bottom d'', and constitutes a box or inclosed space containing the rubber spring e, as shown in Figs. 5 and 50 6. I do not wish, however, to confine myself to the use of a rubber spring, as shown in the drawings, as I may to equal advantage use a

coiled metal spring or a metal spring of other form and construction, as may be desired, without departing from the essence of my invention. 55

Between the rubber e and bottom d'' of the bearing-block d is interposed a metal plate, f, as shown in Figs. 5 and 6.

g is the rocker, having trunnions g' and g'' in its two opposite ends, the former resting loosely in a perforation in the bearing d'', cast in one piece with the bearing-block d, as shown in Figs. 1, 3, 4, and 5. The trunnion g'' is made to rest loosely in a semicircular recess 65 in the forked bearing d', also cast in one piece with the bearing-block d, as shown in Figs. 1, 2, 4, and 5, and after the said trunnion g'' is laid within such forked part d', it is held in position by means of the detachable cap d'' 70 and transverse split pin d'', the latter passing through a perforation made through the forked piece d' and detachable cap d'', as shown in Figs. 1, 2, 4, and 5. The upper side of the rocker g rests against the under side of the 75 rubber spring e, as shown in Figs. 5 and 6, and for the purpose of adjusting the tension of said spring e I employ the screw h, tapped through a screw-threaded perforation in the bottom d'' of the bearing-block d, as shown in 80 Figs. 5 and 6, the lower end of such regulating-screw pressing against the upper side of the metal plate f, as shown, and its upper end having a notched head, h', projecting through a suitable perforation in the sole-plate a, so as to 85 enable the said screw h to be adjusted by means of an ordinary screw-driver or similar tool from the top of the sole-plate a, to regulate the tension of spring e in a quick and simple manner to suit the requirements of the skater. 90

The rocker g has on two opposite sides the stop projections g' g'' serving as stops against the side webs, d' d'', for the purpose of limiting the rocking motion of the rocker g when rocked to its farthest extent in either direction. The lower end of the rocker g terminates as a forked bearing, g' g'', having a transverse perforation for the reception of the spindle i, on which the rollers k k are journaled, as usual. Each roller k is constructed in a peculiar manner, as follows: It is provided on its cylindrical surface with one or more grooves, k', which groove may be of a semicircular, V shape, or other form, as may be desired, the

object of which is to prevent the roller from slipping laterally on the floor, and to make the rollers wear more evenly while the skate is being used. The outer and inner edges, $k'' k'$, 5 are beveled, as shown, to prevent such edges from breaking and chipping off, as well as to prevent the floor from being marred and injured in the rink where the skates are used. The ends of each roller is grooved, as shown in Fig. 6—that is, each roller end is made with an annular groove, k^3 , terminating in its outer portion as an annular ledge or abutment, k^4 , at a right angle, or nearly so, to the end of said roller, and it is adapted to serve as a pocket for and to prevent the liquid lubricant used for lubricating the spindle i to spread outward to the edge of the roller, and thereby preventing the rink floor, as well as the garments of the skaters, from being soiled and greased.

15 I have shown in the drawings the bearing d^3 as a solid piece without any detachable cap and pin, and the bearing d^4 as being forked, and provided with a detachable cap, d^5 , and split 20 pin d^6 ; but I do not wish to confine myself to this exact construction, as I may, if so desired, make both bearings forked, similar to the one marked d^4 , and each provided with detachable cap and 25 split pin, although I prefer to make one bearing solid and the other one forked, and hav-

ing detachable cap and fastening-pin, as shown in the drawings.

If it is desired to detach the rocker g from its bearings, it is only necessary to remove the pin d^6 and cap d^5 , when the rocker may 35 be swung downward until the trunnion g'' is moved out of the forked bearing d^4 , after which the rocker g is drawn out so that the trunnion g' is disengaged from its bearing d^3 . To connect the said rocker g to its bearings, it 40 is only needful to insert trunnion g' into the perforation in bearing d^3 and swing the trunnion g'' into the forked bearing d^4 , after which the cap d^5 is put in position and secured in place by means of the fastening-pin d^6 , as 45 shown in the drawings.

What I wish to secure by Letters Patent, and claim, is—

In a roller-skate, the bearing-block d , having cast integral therewith the perforated bearing d^3 and forked bearing d^4 , in combination with the rocker g , carrying the rollers, and secured in place by means of the cap d^5 and pin d^6 , substantially as shown and described.

In testimony whereof I have affixed my signature in presence of two witnesses.

JOSEPH C. CROPPER.
